Attorney.

UNITED STATES PATENT OFFICE.

JOHN A. CHAPMAN, OF MILWAUKEE, WISCONSIN.

SPRING-GEAR FOR VEHICLES.

SPECIFICATION forming part of Letters Patent No. 392,184, dated November 6, 1888.

Application filed May 15, 1886. Serial No. 202,241. (No model.)

To all whom it may concern:

Be it known that I, JOHN A. CHAPMAN, of Milwaukee, in the county of Milwaukee and State of Wisconsin, have invented certain new and useful Improvements in Vehicles; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention consists, essentially, of a novel arrangement of the springs, of peculiarities in the construction and arrangement of the couplings by which the springs are secured to the axles, of novel means for fastening the reach to the axles, of a new fifth-wheel, and a novel method of mounting the forward bolster thereon, and of certain other details, hereinafter fully described.

In the accompanying drawings like letters refer to the same or similar parts in the several figures.

Figure 1 is a plan view of a vehicle-gear embodying my improvements, slightly modified forms of the spring-couplings being shown at the opposite ends of the axles. Fig. 2 is a side elevation of the same. Fig. 3 is a rear elevation; Fig. 4, a front elevation. Fig. 5 is a side elevation showing modifications of the construction illustrated in Fig. 2. Figs. 6, 7, and 8 show, respectively, on a greatly-enlarged scale, a side and end elevation and a plan view of the forward spring and axle coupling shown in Fig. 2. Fig. 9 is an enlarged view, partly in front elevation and partly in vertical medial section, of the forward spring-clip, fifth-wheel, and bolster-support. Fig. 10 is an end elevation, on an enlarged scale, of the modification of the forward spring and axle coupling shown in Fig. 5. Fig. 11 is an enlarged side elevation of the rear spring and axle coupling shown in Fig. 2, and Fig. 12 is a like view of the modification thereof shown in Fig. 5.

The gear illustrated in the drawings, with slight modifications, is suitable for light or heavy wagons, buggies, carriages, &c.

A A' represent, respectively, the front and rear axles; C C, the forward springs, of the

usual semi-elliptic or double sweep form, are placed one on each side of the axle A, and suspended at the ends by shackles or spring-links L L from the head-plates N N, secured to the top of the axle by axle-clips or axle-yokes M, and bolts m m, as shown more clearly in Figs. 6, 7, and 8.

The plates N N, preferably made of malleable iron, are formed open in the center and with two cylindrical heads, n n, projecting transversely to the axle on each side thereof, as seen in Figs. 6 and 8. The heads n n are perforated transversely to said axle in the same axial line to receive the bolts n' n', by which the shackles or spring-links L L are secured thereto.

I prefer to form the heads n n with trunnions or conical projections l, which are adapted to similar sockets in the spring-links L, about the upper bolt-holes therein, so as to relieve the bolts n' n' of strain, to insure close fitting joints between said head-plates and links, and thereby prevent wear and rattling, bolts c c passing through the lower perforated ends of each pair of links L L, and the interposed head of this spring secures the latter to the head-plates. By thus securing the springs C C independently of each other to the head-plates N it is not essential that the springs should be exactly of the same length, and thereby saves care and labor in making and fitting the parts and greater vexation in putting them together.

The modification shown in Figs. 1, 4, 5, and 10 of the front spring and axle coupling being lighter is better adapted for smaller and lighter vehicles. The plate N', attached to the top of the axle, like the plate N, previously described, is formed with a single head, the ends of which project slightly at each side of said axle, and is perforated transversely thereto to receive the bolt n', Fig. 10.

The spring-links L' L', formed with conical recesses about their upper bolt-holes to receive the conical projections formed on head-plate N', are secured thereto—one on each side of the axle—by a single bolt, n', and are curved outwardly to receive between their lower ends the two springs C C. A single bolt, c', reduced at the ends, passes through the eyes in the heads of said springs and the lower perforations in the links L', and receives at each end outside

of the adjacent link a nut, c^3 . When used as shown in the drawings with the front axle, A, I provide the head-plates N' N' with perforated ears f f, which form shaft-couplings integral with said head-plates.

D D' represent, respectively, the upper and lower sections of the fifth-wheel secured together by the bolt e passing through a central perforation in each, and provided upon their contiguous faces with annular tongues and grooves, by which they are retained in place and the central bolt, e, relieved of strain, Fig. 9. The lower section, D', rests upon and is adapted and secured to each of the springs C 15 C by spring clips or yokes G G and bolts g g, as shown in Figs. 1, 2, 4, 5, and 9. The upper section is formed on its upper face with two perforated ears, d d, between which is pivoted the oscillating bolster E upon the bolt a, as seen in Fig. 4. A single half-elliptic spring, C', employed at the rear end of the vehicle, as shown in Figs. 1, 2, 3, and 5, is mounted above the rear axle, A', and is shackled thereto by means of yokes P, secured to the under side 25 of the axle by clips p p, spring-links O, and bolts c' and o. The links O are secured to the axle at their lower ends by bolts o passing through perforations therein, and a recess in yoke P, and rise one on each side sufficiently 30 above the axle to support the end of said spring above and clear of it. The bolt c' passes through the upper perforations in said links and the interposed head of the spring, which is thus secured at each end. In place of the 35 links O O and bolt o, an integral U-shaped link may be used. The lateral movement or swing of the links O O, permitting the free expansion and contraction of the spring, is limited by the shoulders u u, formed on yokes P.

40 In Fig. 12, illustrating a slight modification of the construction shown in Fig. 11, the spring-loop O' is formed of band-iron, or has its horizontal section connecting the upright limbs flattened, and is supported in a recess formed therefor in the yoke P', which is secured, like the yoke P, before described, to the under side 45 of axle A' by clips p' p'.

The recess in yoke P' is made of sufficient depth to permit the flattened part of loop O' 50 to turn slightly therein and to allow the desired swing or lateral movement of said loop and the free expansion of the spring.

To prevent wear and rattling of the parts, I 55 interpose between the under side of loop O' and yoke P', in a recess formed therefor, a rubber or cushion, t, as seen in Fig. 12. The flattened part of loop O' and the corresponding recess in yoke P', in which it rests, serve to limit, like the shoulders u u shown in Fig. 11, 60 the movement of said loop.

B represents the reach detachably pivoted to the center of the front axle, A, and detachably secured to the center of the rear axle, A', as shown in Fig. 3. Stay-braces b b, attached 65 to said reach B at their front ends, as seen in Fig. 1, diverge toward the rear and are de-

tachably secured to the rear axle, A', by means of ears K K, formed on the yokes P P' of the rear spring-couplings. The ears K K are provided on their inner faces with conical projections k k, adapted to similar sockets formed in the heads b b of braces b, which are secured thereto by bolts k k, as seen in Figs. 11 and 12. By thus constructing the fastenings of the braces b b a close fit is insured and rattling 75 prevented, and the reach may be readily detached and the gear compactly bundled or crated for shipment.

It is obvious that the springs herein shown may be variously arranged to suit the requirements of different vehicles. The spring herein shown at the rear may be used both in front and rear, or the double spring may be similarly used, or the arrangement herein shown reversed.

85

I claim—

1. The combination, with the forward axle of a vehicle, of two half-elliptic springs connected at the ends with said axles, one on each side of the same and parallel therewith, a yoke-plate attached to the upper side of said springs and connecting them at the center, a circle-plate supported upon said yoke and secured thereto at the center by a short pivot-bolt, and a bolster having a jointed connection at the 95 center with said circle-plate, substantially as and for the purposes set forth.

2. The combination, with a vehicle-axle, of spring-loops hinged thereto and projecting upwardly above the same, a spring connected 100 at the ends with the upwardly-projecting ends of said loops above said axle, and stops limiting the vibration of said loops, substantially as and for the purposes set forth.

3. The combination, with the axle A, of yokes P P, secured thereto, loops O O, supported in said yokes, spring C', connected at the ends with said loops and supported thereby over said axle, and stops formed on said yoke and arranged to limit the oscillation of said 110 loops, substantially as and for the purposes set forth.

4. The combination of the axles A A', ears K K, provided with conical projections k k and secured to axle A', reach B, stay-braces 115 b b, secured thereto and having heads b b, recessed to receive said conical projections, and bolts k k, substantially as and for the purposes set forth.

5. The combination, with the axle A', of yokes P P, secured to the under side thereof, loops O O, and spring C', connected at its ends with said loops and supported thereby above 120 said axle, substantially as and for the purposes set forth.

In testimony that I claim the foregoing as my own I affix my signature in presence of two witnesses.

JOHN A. CHAPMAN.

Witnesses:

CHAS. L. GOSS,
JOHN A. GOSS.
